DIAPHRAGM PUMP

Lynn G. Lindsay, Minneapolis, Minn., assignor to
 The Lindsay Ganley Company, Incorporated,
 St. Paul, Minn., a corporation

Application November 15, 1934, Serial No. 753,145

6 Claims. (Cl. 230—170)

My invention relates to diaphragm pumps. While intended more particularly for pumping air, it is obvious that it may be used for pumping other kinds of fluids.

5 Among the objects of the invention are the provision of a pump which is compact with a minimum number of moving parts all of which are easily accessible and which in operation is quiet.

10 I accomplish the objects of the invention by providing a motor housing with a hollow bracket support extending out integrally from one of the housing heads, a diaphragm carried by the bracket support and driving connections for the diaphragm extending down and connected to the motor shaft directly beneath the diaphragm whereby a simple connecting rod is utilized without the provision of any gears. Another feature consists in a chamber with inlet and outlet valves 15 located directly above the diaphragm, the inlet valve consisting of a downwardly opening valve which is weighted to prevent sticking thereof, the result being that the motor will not become stalled even if there should be a leak of backward pressure past the outlet valve into the chamber above the diaphragm.

20 The novel features which I believe to be characteristic of the invention are set forth with particularity in the appended claims. The invention itself, however, both as to its organization and method of operation, together with additional objects and advantages will be best understood from the following description of a specific embodiment when read in connection with the accompanying drawing in which,

25 Fig. 1 is a side elevational view of a motor housing head and bracket integral therewith. Fig. 2 is an end elevational view of what is shown in Fig. 1 and with a small portion in section. Fig. 3 is a view on a reduced scale showing the pump mostly in central vertical section.

30 In the embodiment of my invention shown in the drawing, I provide a motor housing 10 which has a suitable supporting base 12. At one end, the housing 10 has a head 14 and at the other end has a head 16, these heads being provided respectively with bearings 18 and 20 for a motor shaft 22. The head 16 as best shown in Fig. 1 carries an integral bracket support 24 which extends out from the head at a position above the bearing 20 as shown in Fig. 3. The bracket 24 is hollow and at its upper end is provided with a peripheral flange 26 upon which a cup like member 28 having an upwardly convexed bottom 29 is secured by screws 30 passing into threaded open-

ings 32 in the flange 26. These screws also pass through holes disposed around the marginal portion of a flexible diaphragm 34 whereby this marginal portion is clamped between the flange 26 and the bottom of the cup member 28 so that this bottom member and the diaphragm form a chamber. The central portion of the diaphragm is secured to the enlarged upper end 36 of a connecting rod 38 by screws 40 which pass through a plate 42 on the upper side of the diaphragm and are threaded into the member 36.

40 The lower end of the connecting rod 38 is attached by means of a ball bearing device 44 to a crank pin 46 carried by the projecting end of the motor shaft 22 so that the diaphragm is caused to vibrate rapidly and alternately decrease and increase the size of the chamber above the diaphragm. The cup member 28 is provided with external radiating fins 48 and with a cover 50 in which is an inlet opening provided with a filter 52 or strainer 54. A curved enclosing member 54 is detachably held in place below the bracket 24 for protecting the crank pin 46 and the parts associated therewith.

45 The bottom 29 of the cup member 28 is provided with a downwardly opening weighted valve 56 and with an upwardly opening valve 58, the latter being located in an upward extension 60 closed at its upper end by a screw plug 62. The extension 60 above the valve 58 is provided with a lateral opening 64 to which is connected a delivery pipe 66 formed in and leading out from a supporting member 68 mounted above the motor housing 10. The upper side of the support 68 has a diaphragm 70 secured thereto at its periphery, the bottom of the diaphragm at its center being in communication through an opening 72 with the pipe 66 so that the pressure carried by the pipe is imposed upon the bottom of the diaphragm. The support 68 carries an upwardly extending yoke member 74 through the upper portion of which an adjusting screw 76 is threaded. A coiled spring 78 is interposed between the screw 76 and a cup member 80 resting upon the diaphragm 70, a forked arm 82 is pivoted at one end to the yoke member 74 and the forked arm carries trunnions 84 resting in notches on the upper end of the cup 80. Mounted on the other end of the arm 82 is a mercury switch 86 in the circuit which supplies the motor. This switch as shown in Fig. 3 has a normally closed position, but when the pressure in the pipe 66 reaches a certain amount determined by the setting of the screw 76, the end of the arm carrying the switch is caused to swing upwardly thereby open-

ing the switch and stopping the motor. The mercury switch and associated parts are protected by a detachable cap 88. The mercury switch and the parts operatively associated therewith have been described in detail in order that the complete operation of the pump may be clear, but it is not the intention to include these parts in the claims of the present application.

The operation and advantages of my invention will be readily understood in connection with the foregoing description and the accompanying drawing. When the motor in the housing 10 is operated thus rotating the motor shaft 22, the crank pin 46 attached thereto will reciprocate the connecting rod 38 and cause the diaphragm 34 to be rapidly flexed upwardly and downwardly in alteration. Upon the upward stroke, the fluid in the chamber above the diaphragm will be forced out through the outlet valve, the inlet valve 56 of course being closed by the pressure exerted thereon. Upon the downward stroke, a vacuum will be created in the chamber so that fluid will flow from the source of supply past the inlet valve into the chamber during which time the outlet valve is closed. Even should there be a leak backwardly from this valve, the weighting of the inlet valve prevents sticking thereof without any liability of the motor becoming stalled. On account of the compactness of the device, it can be readily placed in any convenient location. The provision of a gearless device with a simple connecting rod construction extending directly down from a diaphragm carried by a bracket support extending out integrally from one of the heads of the motor housing insures quiet and efficient operation. The provision of detachable enclosing members renders it easy to get at all of the enclosed parts for repair thereof. Although I have shown and described certain specific embodiments of my invention, I am fully aware that other embodiments thereof are possible. The invention, therefore, is not to be restricted except insofar as is necessitated by the prior art and by the spirit of the following claims.

I claim:

1. A pump comprising a motor formed with an integral support, a diaphragm carried by said support, a wall mounted above said diaphragm whereby a chamber is formed between said elements, a weighted inlet valve for said chamber mounted in said wall, an outlet valve for said chamber mounted in said wall, and connections between the shaft of said motor and said diaphragm for rapidly vibrating the latter, the provision of said weighted valve serving to prevent stalling of the motor.

2. A pump comprising a motor formed with

an integral support, a diaphragm carried by said support, a wall mounted above said diaphragm whereby a chamber is formed between said elements, an outlet valve for said chamber mounted in said wall, an inlet valve for said chamber mounted in said wall, and driving connections for said diaphragm extending down and connected to the shaft of the motor directly below said diaphragm.

3. A pump comprising a motor formed with an integral support, a diaphragm carried by said support, a cup-shaped member mounted above said diaphragm whereby a chamber is formed between said elements, an outlet valve for said chamber mounted in the bottom of said cup member, an inlet valve for said chamber mounted in the bottom of said cup member, a detachable cover for said cup member, an intake opening for fluid in said cover, a filter for said opening, and connections between the shaft of said motor and said diaphragm for rapidly vibrating the latter.

4. A pump comprising a motor housing having heads, a hollow bracket support extending out integrally from one of said heads, a diaphragm secured at its periphery to the upper portion of said bracket support, a chamber above said diaphragm, an inlet valve for said chamber, an outlet valve for said chamber, and connections between the motor shaft and said diaphragm for rapidly vibrating the latter.

5. A pump comprising a motor housing having heads, a hollow bracket support extending out integrally from the upper portion of one of said heads, a diaphragm secured at its periphery to the upper portion of said bracket support, a chamber above said diaphragm, an inlet valve for said chamber, an outlet valve for said chamber, connections between the motor shaft and said diaphragm for rapidly vibrating the latter, and an enclosing member for said connections detachably held between the lower end of said support and said head.

6. A pump comprising a motor housing having heads, a hollow bracket support extending out integrally from one of said heads, a cup shaped member secured to the upper end of said bracket support, a diaphragm clamped at its periphery between said cup member and bracket support whereby a chamber is formed between said elements, a weighted inlet valve for said chamber mounted in the bottom of said cup member, an outlet valve for said chamber mounted in the bottom of said cup member, a detachable cover for said cup member containing an intake opening, and connections between the motor shaft and said diaphragm for rapidly vibrating the latter.
